SLAT TYPE GRILLE WITH INTERLOCKED SLATS

Marion Morgan Cunningham, Woonsocket, R. I.

Application March 25, 1949, Serial No. 83,459

10 Claims. (Cl. 189—82)

1

My invention relates to a grille of the type composed of intersecting slats which are transversely notched and interfitted at the intersections so that each extends across or substantially across the width of the other, and has reference more particularly to facilities for interlocking the intersecting slats. Grilles of this type are used extensively in artificial lighting to diffuse the light and shield the source of illumination in a manner to avoid objectionable glare.

It has been customary, heretofore, to furnish such grilles in assembled form with the slats permanently secured together at the intersections, usually by welding. Such grille construction with the slats permanently secured together has been objectionable, however, for a number of reasons.

They are bulky to ship in assembled form and require careful crating and packing to avoid damage in transportation. They are also expensive, not only on account of the welding costs but because they do not lend themselves to economical advance production and storage. Only standard sizes for which there is a regular demand can be made for stock and considerable storage space is required for the grilles when assembled. Moreover, they cannot be readily disassembled for cleaning or repairing.

The principal objects of my invention are, to provide an improved slatted grille for lighting fixtures or for other purposes; to construct the grille so that it may be readily and quickly assembled and disassembled; to provide simple and convenient interlocking facilities whereby the grille parts are held securely together in the assembled form; to provide a grille which may be shipped in compact unassembled form and is easily assembled on the job; to permit disassembly of the grille for cleaning or for repairs; and in general, to provide a slatted grille which is economical to manufacture, simple to assemble and disassemble and which avoids objections to previous slatted grille structures; these and other objects being accomplished as pointed out hereinafter and as shown in the accompanying drawings, in which:

Fig. 1 is a top plan view of a grille constructed in accordance with my invention;

Fig. 2 is a perspective view of a fragmentary portion of the grille of Fig. 1, and showing facilities by which it may be suspended;

Fig. 3 is a fragmentary view of a grille slat showing the form of slot arrangement for interlocking with a ball;

Fig. 4 is a plan view of portions of intersecting

2

grille slats in the collapsed form in which the interlocking elements are inserted or removed;

Fig. 5 is a plan view of the slats of Fig. 4 adjusted to the interlocked portion;

Fig. 6 is a perspective view of the end of a grille slat mounted in a marginal frame member;

Fig. 7 is a perspective view showing two intersecting slats with a modified form of locking element;

10 Fig. 8 is a fragmentary view of a slat adapted for use with the disc-shaped locking element of Fig. 7;

Fig. 9 is a perspective view of two cooperating slats about to be assembled and showing a modified form of locking element integral with one of the slats;

Fig. 10 is a plan view of the slats shown in Fig. 9, after assembly;

20 Fig. 11 is a plan view of a modified form of grille construction showing the angle of assembly; and

Fig. 12 is a plan view of the slats of Fig. 11 in final assembled form.

Referring now to the drawing and particularly to Figs. 1 through 6, the grille assembly shown therein is composed of two sets of parallel slats, the slats of one set being indicated by the reference numeral 15 and the slats of the other set, by the reference numeral 16.

The slats 15 and 16 are alike, each made of thin strip stock, provided at uniformly spaced intervals with slots 17 and cut to suitable lengths for the particular grille to be made therewith. These slats may be of metal, plastic or other suitable material, the invention being especially advantageous when plastic strips are employed as such strips cannot be welded. The slots 17 extend from one edge of the strip approximately half way across the width of the strip and are of a width slightly greater than the thickness of the strip stock so as to accommodate portions of the strip freely therein and permit the strips or slats of each set to be readily engaged at the slot locations with the strips or slats of the other set as shown in Figs. 1 and 2.

The slats 15 in Fig. 2 have the slots 17 thereof at the top and the slats 16 have the slots 17 thereof at the bottom and each slat has the portions thereof beyond its slots 17 engaged in the slots 17 of the other set of slats so that each set of slats holds the slats of the other set in laterally spaced parallel relation and each slat is disposed within the width or substantially within the width of the slats of the other set.

When thus arranged, the intersecting slats 15 and 16 form a grille with square openings there-

through bounded by upright portions of the slats as shown in Fig. 2.

For interlocking the two sets of slats 15 and 16 in the thus enmeshed position, each slat 15 and 16 is provided at the inner end of each slot 17 with a circular enlargement 18 located midway between the lateral edges of the slat so that the circular enlargements 18 of the slats 15 are at the same elevation as those of the other slats 16 when the slats 15 and 16 are properly enmeshed, and balls 19 are provided which are engaged in the openings 18 of both the slats 15 and 16 at the intersections thereof.

These balls 19 fit quite closely within the circular enlargements 18 so as to hold the slats 15 and 16 against unmeshing movement, that is, movement in the direction of their width, and the balls themselves are held securely in place by the quarter turn arrangement therearound of the semi-circular halves of the enlargements 18.

Generally it is not necessary to provide balls 19 in all of the intersecting openings 18 as a few properly distributed throughout the area of the grille are sufficient, only three being shown, for example, in the fragmentary portion of the grille illustrated in Fig. 2. In such case, it is preferable to omit the circular enlargements 18 at the inner ends of the slots 17 where an interlocking ball 19 is not employed and merely continue the slots 17 sufficiently, as indicated at 17a in Figs. 2 and 3, so that the slats 15 and 16 will mesh fully together, the slot extensions 17a being preferable at the places where the balls 19 are omitted, as the unoccupied openings 18 would permit passage of light therethrough and this is undesirable.

To insert these balls 19 in the intersecting openings 18, one set of the enmeshed slats 15 and 16 is merely swung relatively to the other set of slats to a somewhat collapsed condition substantially as shown in Fig. 4, in which position the balls 19 may be readily inserted, whereupon the restoring of the enmeshed slats 15 and 16 to the normal right angular relation shown in Figs. 1, 2 and 5 locks the balls 19 in the openings 18 so that the slats 15 and 16 are inseparably locked together. To disassemble the slats 15 from the slats 16, it is merely necessary to collapse the grille to the position shown in Fig. 4 whereupon the balls 19 may be removed.

For suspending a grille of the above construction, hangers 20 may be provided at appropriate places, for example, one near each corner of the grille, each hanger being formed at the lower end with a hook 21 which engages intersecting slats 15 and 16 through the openings 18 at the particular intersection.

These grilles are generally supported in a marginal frame, such as indicated at 22 in Fig. 1, which holds the slats of one set at right angles to the slats of the other set and this frame may consist of channel-shaped bars 23, such as shown in Fig. 5, joined together at the grille corners, or it may consist of frame members of any other suitable design, such as L-shaped and the like. Each channel bar 23 is provided in its central upright web 24 with a series of circular ball openings 25 of the same size and the same distance apart as the openings 18 of the slats 15 and 16, and each opening 25 has a slot 26 extending vertically therethrough from the bottom flange 27 to the top flange 28 of the channel member and continued outwardly in the top flange 28 as indicated at 29 in Fig. 6 to permit insertion of an end portion of a slat 15 or 16 downwardly in the slot 26.

The frame 22 is of such size that ends of all of the slats 15 and 16 engage in slots 26 of the marginal frame and with an opening 18 in each of said ends disposed in ball interlocking relation with the respective opening 25 of the marginal frame 22, and the frame 22 is of such construction that when the slats 15 and 16 are collapsed to the relative angular relation, such as shown in Fig. 4, to receive balls 19 in the ball receiving openings 18 thereof the slats 15 and 16 are at the same time likewise angularly disposed with respect to the surrounding members of the frame 22 to receive balls 19 in the openings 18 which intersect the openings 25 of the frame.

Thus, when the grille is collapsed to receive balls 19 in intersecting pairs of openings 18, 18 of the slats 15 and 16 to interlock the slats, balls 19 may at the same time be inserted in the intersecting pairs of openings 18, 25, and when 20 the grille is thereafter extended to the expanded form of Figs. 1, 2 and 5, the slats ends are interlocked with the frame.

To permit collapse of the frame 22 to conform to the collapsed form of the grille in the operation of inserting or removing the various balls, the frame members (channel irons of Fig. 6, for example) may be hinged together at the corners of the frame, or if preferred, the frame members may be disconnectable at the frame corners for collapsing and detachably securable together in right angular relation in the expanded form of the grille.

Obviously also, it is not necessary for all of the slats 15 and 16 to engage or be interlocked at their ends with the frame 22. They may be interlocked only at selected places around the frame, in which event plain slots 17 with extensions 17a and plain slots 26 without enlargements 25 are employed at the others of said places, or, if desired, only selected slats may be extended sufficiently to engage the frame 22.

Moreover, it is not essential that a frame 22 be employed which extends entirely around the grille. Frame members (such as shown in Fig. 6, for example) may be employed at the opposite ends or at the opposite sides only of the grille and the ends of the slats 16 or of the slats 15, as the case may be, interlocked therewith.

The locking elements for interlocking the meshed slats 15 and 16 may be of shapes other than the ball shape of Figs. 2, 4, 5 and 6. For example, circular discs may be employed as shown at 30 in Fig. 7.

In such case, the slots 17 of the slats 15 and 16, instead of terminating in a rounded enlargement 18 as in Figs. 2, 3 and 6, have a cross slot 31 at the inner ends thereof midway between the lateral edges of the slat, as shown in Figs. 7 and 8, and of suitable size and shape to receive the discs 30. Thus, the combined slots 17 and 31 produce a T-shaped slot, which has the advantage that the portions 32 at opposite sides of the slot 17 are springy and permit greater collapse of the assembled grille to the Fig. 4 position for insertion and removal of the discs 30. 65 Moreover, the discs 30 may be punched from the slats 15 and 16 as indicated at 33 in Fig. 8, if desired.

As an alternative construction, the locking element, instead of being a separate part as in the case of the ball 19 and disc 30, may be a projection on one or both sides of the slats or some of them. The slats 15 and 16 may be provided with slots 17 at their intersection, as shown 75 in Fig. 9, the same as in the Fig. 2 construction

and one of these slots 17 has a circular enlargement 18 at the inner end but with slits 34 extending laterally therefrom so that the portions 35 at the opposite side of the slot are free to flex laterally from the plane of the slot. The slot 17 in the other slat 15 of Fig. 9 terminates in a hemispherical hump 36 pressed laterally from the slat at one side as shown in Figs. 9 and 10.

In assembling a grill of this type, the respective slats 15 and 16 are meshed together until the humps 36 interfere with further meshing, whereupon the assembly is collapsed until the slats 15 of the one set are as nearly parallel as possible with the slats 16 of the other set, and in this collapsed condition the two sets of slats are forced to the full meshing position, after which they are expanded to the normal position at right angles to one another as shown in Fig. 10.

In this final meshing of the slats 15 and 16 of Figs. 9 and 10, the portion 35, of the slat 16, which is at the hump side of the slat 15 bends outwardly as it is forced over the hump 36 and when the slats 15 and 16 are fully enmeshed, this portion 35 springs back to the normal position in the plane of the slat 16.

In this Figs. 9 and 10 construction all of the circular openings 18 may be in one set of the slats and all of the hemispherical bulges 36 in the other set of slats or they may alternate in the slats of both sets. Also, the bulges 36 may be spaced apart with a considerable number of plain slots therebetween and the slots with circular openings 18 slotted at the sides as at 34 may be likewise spaced apart so long as the bulge 36 slots and the circular opening 18 slots mesh together in the assembly and there are sufficient of them throughout the grille area to interlock the two sets of slats.

A modification of this Figs. 9 and 10 construction is shown in Figs. 11 and 12 wherein the slats provided with the bulges are composed of laminations 37 and 38, each of which has an outwardly extending bulge 39 so that there is a bulge at each side of the slot at the places of intersection where the two sets of slats are to be interlocked. The other slats, indicated at 16 in Figs. 11 and 12, are of the same construction as the slats 16 of Figs. 9 and 10 and interlock with the slats 37, 38 in the same manner as the slats of Figs. 9 and 10.

Disassembly of the grilles utilizing humped locking elements is accomplished by swinging the respective sets of slats to the somewhat collapsed position shown in Fig. 11, and pulling the slats apart.

Grilles of the character contemplated in my invention may be made of louvers or slats of any suitable material, metallic, plastic, or otherwise. Likewise, the balls 19 and the discs 30 may be made of various types of materials. For some purposes, a pleasing ornamental or decorative effect can be achieved by using clear or colored plastic or glass balls 19 or discs 30 which will diffuse or refract the rays from the light source.

While I have shown and described my invention in a preferred form, I am aware that various changes and modifications may be made therein without departing from the spirit of the invention, the scope of which is to be determined by the appended claims.

What is claimed is:

1. A grille composed of two intersecting sets of laterally spaced parallel slats which are slotted and meshed together edgewise at the intersee-

tions, the slats of each set being substantially perpendicular to the slats of the other set and means at at least some of the intersections by which the two sets of slats are detachably interlocked with one another in the enmeshed perpendicular relation against separation in the direction of the width of the slats, said means comprising an enlargement of the inner end of each slot of each slat at each place of interlocking thereof, and a separate key at each place of interlocking engaged in the enlargements of both slots, said key being individually locked at each place of interlocking with both enlargements in the perpendicular relationship of the two sets of slats and individually releasable from both of said enlargements when one set of slats is shifted obliquely to the other set of slats, said key having enlargement defining portions of the meshed together intersecting slats arranged circumferentially around the key at substantially equal circumferentially spaced intervals in a plane perpendicular to the length of the slats and which retain and lock the key at the place of intersection of the slats when the slats of one set are perpendicular to the slats of the other set, said enlargement defining portions being relatively movable circumferentially around the key to release the key by movement of one set of the slats to an oblique position relatively to the other set of slats.

2. A grille composed of two intersecting sets of laterally spaced parallel slats which are slotted and meshed together edgewise at the intersections, and means at at least some of the intersections by which the two sets of slats are detachably interlocked with one another in the enmeshed relation against separation in the direction of the width of the slats, said means comprising a circular enlargement at the inner end of each slot of each slat at the intersection thereof, and a ball engaged in the circular enlargement of both slots.

3. A grille composed of two intersecting sets of laterally spaced parallel slats which are slotted and meshed together edgewise at the intersections, and means at at least some of the intersections by which the two sets of slats are detachably interlocked with one another in the enmeshed relation against separation in the direction of the width of the slats, said means comprising a cross slot at the inner end of each slot of each slat at the intersection thereof, and a disc engaged in said cross slots of both slats.

4. A grille composed of two intersecting sets of laterally spaced parallel slats which are slotted and meshed together edgewise at the intersections, and means at at least some of the intersections by which the two sets of slats are detachably interlocked with one another in the enmeshed relation against separation in the direction of the width of the slats, said means comprising a lateral offset from a slot of one of the intersecting slats and a bulge from the side of the other intersecting slat and engaged in said offset.

5. A grille composed of two intersecting sets of laterally spaced parallel slats which are slotted and meshed together edgewise at the intersections, and having at each place of intersection thereof with the slats of the other set a slot which is open at one end and extends inwardly from one lateral edge of the slat in the direction of and part way across the width of the slat toward the opposite lateral edge of the slat, and the slats of each set being engageable in and disengageable

from meshed intersecting relation with the slats of the other set by relative movement of the slats of one set with respect to the slats of the other set in a direction lengthwise of said slots of the slats of both sets, and means at at least some of the intersections by which the two sets of slats are detachably interlocked with one another in the enmeshed relation against separation in the direction of the width of the slats, said means comprising an enlargement at the inner end of the slot of one of the intersecting slats and bulges at the opposite sides of the other slat at the inner end of the slot and engaged in the said enlargement.

6. A grille composed of two intersecting sets of laterally spaced parallel slats which are slotted and meshed together edgewise at the intersections, the slats of each set being substantially at right angles to the slats of the other set and having at each place of intersection thereof with the slats of the other set a slot which is open at one end and extends inwardly from one lateral edge of the slat in the direction of and part way across the width of the slat toward the opposite lateral edge of the slat, and the slats of each set being engageable in and disengageable from meshed intersecting relation with the slats of the other set by relative movement of the slats of one set with respect to the slats of the other set in a direction lengthwise of said slots of the slats of both sets, and means at at least some of the intersections by which the two sets of slats are detachably interlocked with one another in the enmeshed right angle relation against separation in the direction of the width of the slats, said means comprising an individual locking member at each such intersection having a peripheral surface which is spaced from and substantially concentric with and extends at least a part way around the axis of intersection, and at least one of the slats at such intersection having means which is movable relatively to the other slat arcuately along said peripheral surface of the locking member in a direction circularly around said axis to interlock the slats against separation.

7. A grille composed of two intersecting sets of laterally spaced parallel slats which are slotted and meshed together edgewise at the intersections, the slats of each set being substantially perpendicular to the slats of the other set and having at each place of intersection thereof with the slats of the other set a slot which is open at one end and extends inwardly from one lateral edge of the slat in the direction of and part way across the width of the slat toward the opposite lateral edge of the slat, and the slats of each set being engageable in and disengageable from meshed intersecting relation with the slats of the other set by relative movement of the slats of one set with respect to the slats of the other set in a direction lengthwise of said slots of the slats of both sets, and means at at least some of the intersections by which the two sets of slats are detachably interlocked with one another in the enmeshed perpendicular relation against separation in the direction of the width of the slats, said means comprising an individual locking member at each such intersection having a peripheral surface spaced outwardly from and substantially concentrically around the axis of intersection, and at least one of the slats at such intersection having means which is movable peripherally around the locking member along said peripheral surface thereof to and from the other slat in a direction circularly around the

axis of intersection to interlock the slats against separation.

8. A grille composed of two intersecting sets of laterally spaced parallel slats which are slotted and meshed together edgewise at the intersections, the slats of each set being substantially perpendicular to the slats of the other set and having at each place of intersection thereof with the slats of the other set a slot which is open at one end and extends inwardly from one lateral edge of the slat in the direction of and part way across the width of the slat toward the opposite lateral edge of the slat, and the slats of each set being engageable in and disengageable from meshed intersecting relation with the slats of the other set by relative movement of the slats of one set with respect to the slats of the other set in a direction lengthwise of said slots of the slats of both sets, and means at at least some of the intersections by which the two sets of slats are detachably interlocked with one another in the enmeshed perpendicular relation against separation in the direction of the width of the slats, said means comprising an individual locking member at each such intersection having an arcuate surface which is spaced outwardly from and substantially concentric with the axis of intersection, and at least one of the slats having the slot thereof at the intersection provided with a lateral enlargement which is movable relatively to the other slat peripherally along the arcuate surface of the locking member in a direction circularly around said axis to cooperate with the locking member in interlocking the slats against separation.

9. A grille composed of two intersecting sets of laterally spaced parallel slats which are slotted and meshed together edgewise at the intersections, the slats of each set being substantially perpendicular to the slats of the other set and having at each place of intersection thereof with the slats of the other set a slot which is open at one end and extends inwardly from one lateral edge of the slat in the direction of and part way across the width of the slat toward the opposite lateral edge of the slat, and the slats of each set being engageable in and disengageable from meshed intersecting relation with the slats of the other set by relative movement of the slats of one set with respect to the slats of the other set in a direction lengthwise of said slots of the slats of both sets, and means at at least some of the intersections by which the two sets of slats are detachably interlocked with one another in the enmeshed perpendicular relation against separation in the direction of the width of the slats, said means comprising a separate locking member at each such intersection which is individually removable therefrom and has an arcuate surface which is spaced outwardly from and substantially concentric with the axis of intersection, and at least one of the slats at such intersection having the slot thereof at the intersection provided at each side of the axis of intersection with a lateral enlargement which is movable relatively to the other slat peripherally along the arcuate surface of the locking member in a direction circularly around said axis to cooperate with the locking member in interlocking the slats against separation.

10. A grille composed of two intersecting sets of laterally spaced parallel slats which are slotted and meshed together edgewise at the intersections, and having at each place of intersection thereof with the slats of the other set a slot which

is open at one end and extends inwardly from one lateral edge of the slat in the direction of and part way across the width of the slat toward the opposite lateral edge of the slat, and the slats of each set being engageable in and disengageable from meshed intersecting relation with the slats of the other set by relative movement of the slats of one set with respect to the slats of the other set in a direction lengthwise of said slots of the slats of both sets, and means at at least some of the intersections by which the two sets of slats are detachably interlocked with one another in the enmeshed relation against separation in the direction of the width of the slats, and a marginal frame to which the ends of at least some of the slats are detachably interlocked, all of said detachably interlocked slats being releasable upon adjustment of one set of slats obliquely to the other set of slats and to the frame, said slats having end portions which intersect portions of 20 said marginal frame and some of said intersecting portions having matching openings at the intersection and a locking member seated in said openings interlocking said intersecting portions

5 to one another, said locking member having a peripheral surface spaced outwardly from and extending substantially concentrically around the axis of intersection, and at least one of the intersecting portions having means which is movable peripherally around the locking member along said peripheral surface thereof to and from the other intersecting portion in a direction circularly around the axis of intersection to interlock the slats against separation.
